KARL WIESER, OF RÜTTENSCHIED, NEAR ESSEN-ON-THE-RUHR, GERMANY,
ASSIGNOR TO FRIED. KRUPP, OF ESSEN-ON-THE-RUHR, GERMANY.

PERCUSSION-FUSE FOR EXPLODING SHELLS.

SPECIFICATION forming part of Letters Patent No. 757,165, dated April 12, 1904.

Application filed April 30, 1902. Serial No. 105,349. (No model.)

To all whom it may concern:

Be it known that I, KARL WIESER, a subject of the Emperor of Germany, and a resident of 34 Friederikenstrasse, Rüttenscheid, near Essen-on-the-Ruhr, Germany, have invented certain new and useful Improvements in Percussion-Fuses for Exploding Shells, of which the following is a specification.

Percussion-fuses have heretofore been provided with an arrangement for so regulating the detonation of the exploding charge that it follows the ignition of the fuse with or without delay—that is to say, either at the instant the projectile reaches the target or with a sufficient retardation to insure the explosion taking place after the projectile has penetrated the target. The adjustment of the percussion-fuse corresponding to these two results may be designated for convenience as the "impact" position or the "delay" position.

The present invention constitutes a new embodiment of percussion-fuse for attaining the aforesaid object, which provides for a rapid and easy changing of the condition of the fuse from delay to impact, and vice versa, by arranging a cock in a channel which forms direct or immediate communication between the igniting-chamber of the percussion-fuse and the bursting charge of the shell, through the medium of which cock the channel may be opened or closed.

The accompanying drawings, forming part of this specification, show an embodiment of the invention by way of illustration in its two positions or conditions of use.

Figure 1 is a vertical section through the axis of the fuse and the axis of the cock-spindle with the channel opened; Fig. 2, a corresponding section with the channel closed; Fig. 3, a plan view corresponding to Fig. 1, and Fig. 4 a plan view corresponding to Fig. 2.

Percussion-fuses heretofore made have employed a needle-bolt A, check-ring B, and the safety-spring C, arranged immediately in a bore of the fuse-body F, and the igniting-pellet D, resting in a screw-cap which closes the bore, while from the igniting-chamber of the percussion-fuse two different passages lead toward the interior of the shell. One of these

passages is formed by an oblique channel R, 50 extending from the igniting-chamber and terminating in a longitudinal channel S, running parallel to the axis of the fuse, extending forward to the head of the fuse-body and receiving at its base a portion K of rapidly-burning 55 powder, which reinforces the flash of the igniting-pellet. The channel S is in communication with a bore T of the fuse-body, which is filled with a longitudinally and transversely bored charge M of rapidly-burning powder 60 and closed by a screw-plug L, provided with a longitudinal bore O. The second connection between the igniting-chamber and the interior of the shell is provided by the channel U, which is filled with a portion N of slowly- 65 burning powder and discharges into the bore T. If the channel R is open, the flash of the fuse-pellet communicates with the rapidly-burning powder K, thence to the rapidly- 70 burning charge M, and then to the interior of the shell, and detonation of the bursting charge takes place instantly upon impact. If, however, the oblique channel R is closed, the flash from the fuse-pellet only ignites the slow-burning charge N and is communicated from 75 it to the rapidly-burning charge M less rapidly, so that the last-named charge M detonates the bursting charge only after the elapse of sufficient time to permit penetration to have 80 taken place.

According to the present invention the device for cutting off the channel R, which forms the immediate communication between the igniting-chamber of the percussion-fuse and the bursting charge, consists of a cock V, which 85 at the height of the opening of channel R into channel S has a bore E, which leads into the longitudinal bore G. The latter terminates above the charge of rapidly-burning powder at the base of the channel S. The cock V carries on its upper end a spring-arm H, for 90 which two recesses J J² are provided in the fuse-head.

In the position of use illustrated in Figs. 1 and 3 the cock V is in the position in which 95 its spring-arm H rests in the recess J and its bores E G establish communication with the open channel R. In consequence when the

igniting-needle pricks the igniting-pellet in the well-known manner upon the impact of the projectile the fire-flash proceeds without delay through the bore of the needle-bolt and through the channels R, E, G, S, T, and O to the bursting charge, so that the shell explodes at the instant of its impact.

If the ignition is to follow with delay, the arm H of the cock is released by hand from the rest J' and moved in the direction of the arrow α , Fig. 3, until it springs into the recess J², Fig. 4. The cock V then takes the position shown in Fig. 2. In this position of the cock the channel R is closed off from the channel S, so that the ignition of the bursting charge can take place only after the combustion of the retarding-charge N, contained in the channel U.

Having thus described the said invention, the following is what is claimed as new therein:

1. In a percussion - fuse, the combination with a fuse-stock, and a non-rotatable primer, of two passages communicating ignition to the bursting charge, a delay-action device in one of said passages, and manually-operated means rotatable independently of the primer to one position to open the other passage and to another position to close it.
2. In a percussion - fuse, the combination with a fuse-stock, and a non-rotatable primer, of two passages communicating ignition to the bursting charge, a delay-action device in one of said passages, a cock turning independently of primer in the other passage and movable

to one position to open said passage, and to another position to close said passage.

3. In a percussion - fuse, the combination with a fuse-stock, and a non-rotatable primer of two passages communicating ignition to the bursting charge, a delay-action device in one of said passages, a cock turning independently of primer in the other passage and movable to one position to open said passage, and to another position to close said passage, and means for fixing the cock in its respective positions.

4. In a percussion-fuse of substantially the character herein described, having two passages communicating ignition a delay-action device in one of said passages, a cock turning in and arranged to open and close the other passage, a spring-arm on said cock, and means engaging the spring-arm in the opened and closed positions of the cock.

5. In a percussion-fuse of substantially the character herein described, having two passages communicating ignition, a delay-action device in one of said passages, a cock turning in and arranged to open and close the other passage, a spring-arm on the free end of the cock, and recesses J', J², in the fuse, into which the spring-arm enters at the respective ends of the cock's turning movement.

The foregoing specification signed at Dusseldorf this 17th day of April, 1902.

KARL WIESER.
